SEPARABLE HINGE CONNECTION

Edwin L. Harmon, Groton, N. Y., assignor to L C Smith & Corona Typewriters, Inc., Syracuse, N. Y., a corporation of New York

Original application October 18, 1935, Serial No. 45,530. Divided and this application February 18, 1937, Serial No. 126,372

7 Claims. (Cl. 16—175)

The invention relates to improvements in separable hinge connections.

A purpose of the invention is to provide a simple, sturdy, inexpensive and highly efficient hinge connection between two elements which will permit ready and easy connection and disconnection of said elements and will hold said elements hinged together with said elements latched against accidental disconnection.

10. Another purpose of the invention is to provide an improved and efficient separable hinge connection between two elements whereby the elements may be swung to and from edgewisely abutted relation, are latched against accidental disconnection in all hingedly connected relations of said elements, and the latching means preventing accidental disconnection of said elements is inaccessible for release from one face of said elements at all times and is releasable by a finger 20 piece exposed only when said elements are swung about the axis of their hinge connection out of edgewisely abutted relation.

A further purpose of the invention is to provide an efficient separable hinge connection for the 25 base and cover sections of a portable carrying and enclosing case of the kind hereinafter described for portable typewriting machines.

It is also a purpose of the invention to obtain any and all of the advantages with respect to 30 construction and to operation inherent in the construction which is shown in the accompanying drawing and hereinafter particularly described as constituting the preferred embodiment of the invention.

35. In the accompanying drawing illustrating the preferred embodiment of the invention:

Fig. 1 is a detail perspective view showing the left hand rear corner of a carrying case for a portable typewriting machine, with the cover section 40 of the case swung upward and rearward relatively to the base section into a substantially vertical position;

Fig. 2 is a fragmentary rear end view of the case with the cover section swung to closed position on the base section;

Fig. 3 is a sectional view on the line 3—3 of Fig. 2;

Fig. 4 is a sectional view on the line 4—4 of Fig. 2, but showing the case with its cover section 50 swung fully open; and

Fig. 5 is a sectional view taken through the case on the same line as Fig. 3 but showing the mode of connecting and disconnecting the cover and base sections of the case.

55. This application is a division of my co-pending

application Serial No. 45,530, filed October 18, 1935, and only so much of the carrying case for a typewriting machine disclosed in said co-pending application as is necessary to an understanding of the subject matter of invention claimed in the present application is shown in the accompanying drawing.

This carrying case is of the flat box-like type which comprises a base section and a cover section, the base section having a rectangular bottom wall which is provided with an upstanding rim extending around all four edges of said wall, and the cover section having a rectangular top wall which is provided around its four edges with a depending rim adapted to abut edge to edge with, or seat edge to edge on, the rim of the base section when the case is closed to encase a portable typewriting machine mounted on the base section. The case is provided with a handle (not shown) attached to the front end of the cover 10 section, and is also provided at its front end with a suitable spring lock means (not shown) for locking the rims of the case sections together at the front end of the case to prevent unauthorized opening of the case.

In the drawing, 10 is the bottom wall or base-board of the base section of the case, 12 is the rear wall of the rim of the base section, 13 the side walls of the rim of the base section, 17 is the rear wall of the rim of the cover section, and 18 are the side walls of the rim of the cover section which connect the front and rear walls of the rim of the cover section. A pair of separable and identical hinges connect the rear rim walls 12 and 17 of the two case sections, the two hinges (one of which is shown in the drawing) being located closely adjacent the right and left hand sides of the case, and each hinge including a latch for preventing accidental and unauthorized separation of the hinge. Two wide notches 21 (only one of which is shown) are formed in the top edge of rim wall 12 of the base section, one near each end of said rim wall, to receive and provide clearance for parts of the hinges as hereinafter more fully described. That one of the two identical hinges referred to, which is shown in the drawing, will now be specifically described.

The pintle-carrying or base-section hinge leaf is formed of sheet metal and comprises a flat attachment portion 22 lying against the inner face of rim wall 12 of the base section of the case and secured thereto by means of a pair of rivets 23, a flat pintle-carrying portion 24 bent at a right angle to said attachment portion and overlying and seated upon the bottom wall of one 50 55

of the notches 21, two lugs extending rearward from opposite ends of portion 24 and rolled upward and forward and downward to form a pair of pintle rolls 25 slightly offset rearward from 5 the outer or rear face of rim wall 12, and a pair of stop lugs 26 pendent from the inner edges of said rolled lugs and abutting the outer face of rim wall 12. A metal pintle rod 27 is fixedly held at its ends in pintle rolls 25 and extends horizontally between said rolls behind rim wall 12 10 opposite notch 21.

The hook-carrying or cover-section hinge leaf is formed of sheet metal and comprises a flat attachment portion 28 lying against the inner face 15 of rim wall 17 and secured to the said rim wall by a pair of rivets 29, a flat hook-carrying portion 30 bent at a right angle to portion 28 and overlying and abutting the lower edge of rim wall 17, and a hook portion or half-roll portion 31 20 for separable engagement with the pintle rod 27. The hook portion 31 extends rearwardly and downwardly and forwardly from portion 30 to form a hook located slightly to the rear and below the lower edge of rim wall 17 with the 25 open throat of the hook facing forward. The nose of the hook is reduced in width to fit between stop lugs 26 and to provide stop shoulders 32 on the hook adapted to abut lugs 26 to limit opening swinging movement of the cover, the 30 remaining portion of the hook being wide enough for its side edges to abut the inner ends of the pintle rolls 25 and prevent axial movement between the hinge leaves.

Part 28 of the hook-carrying hinge leaf has a 35 latch guiding lug 33 struck up therefrom midway its side edges and has threaded therein midway its side edges, and between said lug 33 and the lower edge of rim wall 17, a shouldered stop and guide screw 34 for the hinge latch. The lug 33 40 and screw 34 lie in a plane perpendicular to the plane of the lower edge of rim wall 17 and guide the hinge latch to slide perpendicularly to the top wall of the cover section and parallel to rim wall 17. The latch is formed of sheet metal and 45 comprises a metal strap having a relatively long guiding leg portion 35 slidable on part 28 of the hook-carrying leaf, a short throat-closing or pintle rod engaging leg portion 36 which lies parallel to the longer leg portion 35 and slidably 50 abuts the outer face of rim wall 17 to assist in guiding and bracing the latch, and a flat thrust-receiving portion 37 connecting said leg portions. Lug 33 and screw 34 extend respectively through 55 aligned slots 38 and 39 which are formed in, and extend longitudinally of, leg 35 of the latch.

A coiled spring 40, one end of which is confined in a bore 41 which extends upward in rim wall 17 from the lower edge of said rim wall, bears at its other end on thrust-receiving portion 60 55 of the latch and normally holds the latch in its projected latching position shown in Figs. 1 and 3, movement of the latch by the spring being limited by stop screw 34, as shown in Fig. 3. When the latch is projected by its spring 40, part 36 of the latch extends far enough across 65 the open throat of hook 31 to engage over the pintle rod 27 and prevent the hook from separating from the pintle rod. The hook-carrying hinge leaf is provided with a clearance aperture 70 42 for parts 36 and 37 of the latch. By pressing against the outer face of part 37 of the latch, the latch may be slid into the release position shown in Fig. 5 wherein part 37 is within the aperture 42 and part 36 is shifted to entirely 75 uncover or leave unobstructed the open end or

throat of the hook 31 to permit connection and disconnection of the hinged case sections.

Held to rim wall 12 at the outer face thereof slightly below and substantially midway the length of each of the pintle rods 27 of the case 5 hinges, and slightly below the level of lugs 26, of each hinge, is one of a pair of hemispherical metal buttons 43 which project rearward from rim wall 12 slightly farther than the pintle rolls 25 and hooks 31 of the hinges. The buttons 43 10 have tangs or prongs 45 driven into the rim wall 12.

To open the case and detach the cover section, the lock (not shown) at the front end of the case is released and the cover swung open. It is 15 then simply necessary for the operator to grasp the two lower corners of the opened cover and press rearward with the thumbs on the now exposed and accessible thrust-receiving portions 31 of the hinge latches, whereupon the cover may 20 be lowered as in Fig. 5 to disengage the hooks 31 from the pintles, and the hooks will, upon further lowering movement of the cover, be guided downward and outward from under the pintle rods by the cam or rounded surfaces of buttons 43 25 and by the stop lugs 26.

To re-connect the cover and close the case the cover is grasped in the hands in up-ended position and pulled forward with the hooks resting on the upper halves of buttons 43 and with parts 37 30 of the latches abutted against the pintle rods, thus causing the latches to be pressed into release position and the cover to rise, the buttons 43 camming the cover upward and, in connection with lugs 26, guiding the hooks closely up 35 under the pintle rods into the position shown in Fig. 5. A slight upward lift of the cover will then engage the hooks about the pintle rods and release the latches for automatic projection by their springs 40 over the pintle rods, thus locking 40 the hinges against separation. The cover may then be swung closed, and be locked by the lock (not shown) at the front of the case.

The notches 21 afford clearance for portions 30 and 24 of the hinge leaves, and also afford 45 clearance for the projected ends of the latches when the case is closed so that closure of the case will not release the latches. The pressure-receiving portions 37 of the latches are only accessible 50 when the cover is swung open.

What I claim is:

1. A separable hinge comprising a hook, a leaf to which said hook is fixedly held, a pintle passable through the throat of said hook and engaged between its ends in said hook, a reciprocable latch mounted on said leaf to slide crosswise of the leaf and transversely of the pintle into and out of a latching position in which the latch is projected across the throat of the hook to block passage of the pintle through said throat, a spring for projecting said latch into latching position, said latch having adjacent said hook an end face for receiving pressure to release the latch, and a second leaf to which the opposite ends of the pintle are rigidly held and which covers and uncovers 65 said pressure-receiving end face of said latch in different angular relations to said hinge leaves.

2. A separable hinge comprising two hinge elements separably hooked together for relative pivotal movement, a latch slidably held to one of 70 said elements for sliding into and out of a latching position in which it blocks unhooking of said elements and having an actuating portion which is respectively exposed for operating access thereto and rendered inaccessible by relative 75

pivotal movement between said separably hooked elements.

3. For hingedly and separably connecting the base and cover sections of a typewriter enclosing case the said sections of which have rims which abut edge to edge when the case is closed, a hinge comprising a pair of leaves adapted for attachment to the inner faces of the respective case section rims and provided at their adjacent 10 ends respectively with a hook and a pintle which are in separable pivoted engagement and are so carried by the leaves as to be located close to the outer edges of the case section rims when the leaves are attached to the inner faces of the rims, 15 a latch slidably mounted on the leaf which is provided with the hook for reciprocation of the latch across the throat of the hook and transversely of the pintle into and out of a latching position in which the latch blocks passage of the 20 pintle through the throat of the hook, and a spring for projecting said latch normally into said latching position, said latch having an end face for receiving pressure to release the latch and being so mounted on its supporting leaf that 25 said end face will be substantially entirely confined between the hinged rims when the case is closed.

4. A separable hinge comprising, in combination, a pair of hinge leaves separably and pivotally hooked together, and a sliding latch having an actuating portion and carried by one of said leaves both for sliding of the latch relatively to said leaf into and out of a latching position in which the latch blocks unhooking of 30 the leaves and for swinging in unison with said leaf into and out of a position in which the actuating portion of the latch is inaccessible, said latch being normally spring-urged into latching position and being releasable by pressure on said 35 actuating portion.

5. A separable hinge for connecting edgewise abuttable rim walls of the base and cover sections of an enclosing case for portable typewriting machines, comprising two hinge leaves having attachment portions for fixing thereof to the inner faces of the rim walls to be hinged, a hook extending laterally from the attachment portion of one leaf with the throat of the hook at the opposite side of the shank of the hook from that at 40 which the attachment portion is located, a pintle engaged in said hook and movable through the throat of the hook, pintle supporting means extending laterally from the attachment portion of 45

the other leaf to said pintle at opposite sides of the hook, a latch having a supporting portion slidably held to the hook-carrying leaf for reciprocation of the latch across the throat of the hook transversely of the pintle into and out of a 5 latching position in which the latch blocks passage of the pintle through the throat of the hook, said latch having an actuating portion which extends laterally from its supporting portion in the same direction as the hook and terminates at its 10 free end in a hook-throat blocking portion movable into and out of blocking position by reciprocation of the latch.

6. A separable hinge as claimed in claim 5, wherein the pintle supporting means is provided 15 with means for guiding the hook into engagement about the pintle.

7. A hinge comprising a pintle-carrying leaf, a latch and hook carrying leaf, a sliding latch, and a pintle rod fixedly held at both of its ends to the 20 pintle-carrying leaf, said pintle-carrying leaf comprising a plate-like attachment portion and a pintle-carrying portion bent at a right angle to the plane of said attachment portion and having two lugs projecting from its outer end and rolled 25 about the ends of the pintle rod, said rolled lugs having lugs extending from their adjacent edges and located opposite the attachment portion, said hook-carrying leaf comprising a plate-like attachment portion and a hook-carrying portion 30 extending at a right angle thereto with the open throat of the hook at the opposite face of the hook-carrying portion from the attachment portion of the leaf, the hook being hooked over the pintle rod between said rolled lugs and said other 35 lugs and having stop shoulders engageable with said other lugs to limit pivotal movement between the hinge leaves in a direction which swings their attachment portions into angularly disposed relation, said latch comprising a metal 40 strap having two spaced parallel legs joined at one end only, said latch at the joined end of the legs being slidably extended through an aperture in the hook-carrying part of the hook-carrying leaf and having that one of its legs which is farthest from the hook slidably held to and guided to move endwise on that face of the attachment portion of said leaf which is farthest from the hook, the legs of the latch extending transversely of the pintle rod and of the open 45 50 throat of the hook.

EDWIN L. HARMON.
